REGULATOR STEM SEAL

John J. Delany, Brooklyn, N. Y., assignor to Delany Realty Corporation, New York, N. Y., a corporation of New York

Application November 11, 1944, Serial No. 562,957

1 Claim. (Cl. 286—26)

1 This invention relates to regulating elements accessible from the outside of a casing containing a fluid under pressure in excess of atmospheric pressure so as to permit of adjustments of means within the casing while precluding leakage of fluid from the inside of the casing and while not necessarily restricted thereto, the same is ideally adapted for use in connection with flush valves so as to provide means adjustable from the exterior thereof for regulating the timing or length of the flushing operation without permitting of leakage of water around the regulating means.

The invention broadly comprehends a device of the indicated character which is extremely simple in its construction and mode of operation which may be inexpensively produced as a part of the apparatus with which it is associated and which effectively functions to prevent leakage without appreciable wear and the necessity of adjustment to compensate therefor, while taking the place of more complicated means such as stuffing boxes, packing glands and the like which are more expensive and require frequent adjustment as well as replacement of the packing.

More particularly the invention is directed to a device of the character set forth which includes a casing containing a fluid under pressure in excess of atmospheric pressure in which the casing is formed with an aperture opening through the inner and outer surfaces thereof with a regulating element fitted therein and adjustable longitudinally of the aperture and having its inner terminal protruding into the casing for engagement with the means to be regulated, wherein the inner surface of the casing surrounding the aperture is formed with a recess with a compressible elastic sealing member having an opening snugly fitted over the regulating element and inherently contracted thereabout and arranged within the recess for rendering the casing fluid tight in the region of the regulating element.

With the above recited and other objects in view, the invention is more fully described in the following specification, particularly pointed out in the appended claim and illustrated in the accompanying drawings, wherein—

Fig. 1 is a side view of a flush valve with parts broken away and equipped with a regulating screw and sealing means therefor constructed in accordance with the present invention.

Fig. 2 is an enlarged fragmentary sectional view showing the interfitting of the rib and groove of the sealing member prior to the application of pressure thereto.

Fig. 3 is a detail perspective view of the sealing member per se.

Referring to the drawings by characters of reference, A designates the casing of a diaphragm

5 type flush valve which is merely illustrative of one of the uses of the invention to demonstrate its practical application. As is usual in this type of flush valve, the upper portion thereof within the cap section B constitutes a water pressure chamber C located above the diaphragm valve member D. An upper valve element E is normally disposed in closed relation to a seat F which surrounds the central passageway G through the diaphragm valve member D and which upper valve element E is canted and displaced from its seat by the engagement of the terminal H of a handle J with the actuator stem K upon manipulation of said handle.

10 Heretofore, regulation of the length or duration of the flushing operation has been set before the valve casing is closed and any correction thereto or subsequent regulation thereof has required the removal of the cap section B for gaining access to the parts for making proper adjustment.

15 The present invention is directed to means accessible from the outside of the casing which contains the fluid under pressure for the purpose of regulating or adjusting the parts within the casing while avoiding leakage and, as illustrated in the present disclosure the removable cap section C is formed with an aperture 10 which is threaded and with which the threaded head 11 of a regulating element or screw L is engaged to adjust the same longitudinally of the aperture by turning thereof in opposite directions. The element or screw L is formed with an inwardly directed reduced shank 12 which protrudes into the interior of the casing to perform its function.

20 In the flush valve, as illustrated, the inner terminal of the shank 12 constitutes an adjustable abutment with which the upper valve element E engages to limit and control the opening of the same with reference to its seat F to thereby regulate the duration of the flushing operation. In order to prevent leakage through the aperture 10 and around the head 11 of the screw L a compressible elastic sealing member 25 M is utilized which may be made of rubber or any equivalent material and said member is formed with an opening 13 of a size to snugly fit and inherently contract about the shank 12 of the screw L so as to prevent leakage through the opening 13 between the wall thereof and the periphery of the shank. The sealing member or washer M is arranged within a recess 14 formed in the inner surface of the cap section B of the casing in surrounding relation to the inner end of the aperture 10 and the upper face 15 of the sealing member M is forced into engagement with the inner wall 16 of the recess by the pressure within the casing to prevent egress of the fluid therefrom between the face 15 and said wall 16 of the recess.

If desired, the sealing member or washer M may be provided with an endless rib 17 on its upper face and the inner wall of the recess with a mating groove 18 to provide a more effective seal. Preferably the rib 17 as shown in Fig. 2 is of greater height than the depth of the groove and of lesser width than the width of the groove so that the fluid pressure within the casing depresses the height of the rib and increases its width so as to fill the groove and render the action of the sealing member more effective in preventing any leakage between the face 15 and the inner wall 16.

Under this construction and arrangement, it is apparent that turning of the regulating screw L to adjust the same toward or away from the upper valve E accomplishes the regulation of the flushing operation without the necessity of opening the valve casing while the pressure within the casing impinging upon the sealing member or washer M prevents displacement or leakage. It is obvious that within the scope of the invention the regulator screw may be employed for other purposes than that disclosed without departing from the spirit of the invention.

What is claimed is:

In a device of the character set forth, a casing adapted to contain a fluid under pressure in excess of atmospheric pressure, said casing having a recess in its inner surface defined by an inner wall and an angularly related side wall extending inwardly from said inner wall, said recess being formed with an aperture opening at its opposite ends respectively through the outer surface of the casing and the inner wall of the recess, a regulating element fitted within and adjustable longitudinally of said aperture with

its inner terminal extending through and protruding from the recess into said casing, a compressible elastic sealing member having an opening compressed about the regulating element and arranged within the recess for preventing leakage through the aperture in the casing, said inner wall of the recess being formed with an endless groove spaced from and disposed in surrounding relation to said aperture therein and said sealing element being formed with an endless rib on the face thereof confronting the inner wall of the recess, said rib being of greater height than the depth of the groove and of lesser width than the width of the groove to permit the fluid pressure within the casing to depress the height and increase the width of the rib so as to fill the groove and render the action of the sealing member more effective.
